Attorneys

UNITED STATES PATENT OFFICE.

WALTER W. WELPLEY, OF DETROIT, MICHIGAN.

TOOTHPASTE HOLDER.

Application filed November 14, 1921. Serial No. 514,875.

To all whom it may concern:

Be it known that I, WALTER W. WELPLEY, a citizen of the United States of America, residing at Detroit, in the county of Wayne and State of Michigan, have invented certain new and useful Improvements in Toothbrush Holders, of which the following is a specification, reference being had therein to the accompanying drawings.

10 My invention aims to provide a tooth brush holder made of two pieces of material, detachably connected together, with one piece of material bent and shaped to afford a shelf and a back plate, and the other piece of material bent and shaped to afford inclosures for one or more brushes. The brushes are adapted to be frictionally retained within the inclosures by struck-out resilient tongues or members of the back plate, and brushes can be easily inserted in the holder and retained in a sanitary condition. The manner in which the pieces of material are articulated to form the holder permits of the holder parts being separated 20 and cleaned, and one of the holder parts conceals the fastening means employed for attaching the holder to a wall or other support.

25 My invention further aims to provide a tooth brush holder that is rust proof, well ventilated, and easy to mount on a wall in a bathroom or other compartment, and the construction entering into the tooth brush holder will be hereinafter described and then claimed.

Reference will now be had to the drawing wherein

30 Figure 1 is a front elevation of the tooth brush holder;

35 Fig. 2 is a vertical sectional view taken on the line II—II of Fig. 1;

40 Fig. 3 is a horizontal sectional view taken on the line III—III of Fig. 1;

45 Fig. 4 is a plan of the tooth brush holder, and

Fig. 5 is a front elevation of the back plate of the tooth brush holder.

In the drawing the reference numeral 1 denotes a back plate that is rectangular in 50 front elevation and has its ends provided with inturned flanges 2 disposed in parallelism with the front face of the plate 1 to provide a pair of vertical guides that are

open at the upper and lower ends thereof.

The upper edge of the back plate terminates in a horizontal ledge or shelf 3 having its front edge upturned, as at 4 and more or less ornamental, said upturned edge being disposed at a right angle to the shelf 3 and parallel to a wall or support 5 to which the back plate 1 may be attached. In order that this may be conveniently accomplished, the back plate has openings 6 for nails 7 or other fastening means that may extend into the wall 5 and anchor the back plate relative thereto. With the back plate so held a tooth paste tube, container, or other article 8 may be safely placed on the shelf 3 and supported thereby, as indicated by dot and dash lines in Fig. 5.

70 Detachably connected to the back plate 1 is a compartment plate 9 which is scalloped or bent to afford a plurality of parallel compartments or inclosures 10, said compartments being separated by doubled portions 11 of the compartment plate 9. The ends of the compartment plate 9 have lateral flanges 12 that are mounted in the guides formed by the back plate 1 and the flanges 2 and by reason of the shelf 3 overhanging the upper ends of the flanges 2, it is necessary to slide the flanges 12 upwardly under the lower ends of the flanges 2 when assembling the compartment plate 9 relative to the back plate. With the compartment plate mounted on the back plate the doubled portions 11 of the compartment plate will bear against the front face of the back plate and the upper ends of the compartments or inclosures 10 will be closed by the shelf 3, while the lower ends of the compartments or inclosures will be open so that tooth brushes may be inserted in the compartment.

90 The back plate 1 has a plurality of struck out resilient tongues or members 13 corresponding in number to the compartments and it is into said compartments that the resilient members 13 extend to bear against the back 14 of a tooth brush 15 and cause the bristles of said brush to bear against the compartment plate thus causing the tooth brush to be frictionally held, as shown in Fig. 2. The handle of each tooth brush will extend downwardly from the holder so that the tooth brush may be gripped and with-

drawn from its compartment, and in order that there may be ventilation within each compartment, the shelf 3 is provided with a series of openings 16 corresponding in number to the toothbrush compartment.

The two parts of the holder are preferably made of light and durable metal, for instance aluminum that will be practically rust proof and susceptible to a polish that will 10 permit of the holder in its entirety presenting a neat and attractive appearance when mounted on a wall or other support. The compartment plate will conceal the nails 7 or fastening means by which the holder is 15 suspended, and since the shelf 3 affords a support for a tooth paste tube it will always be convenient for the user of a tooth brush.

Since the tooth brush holder is simple in 20 construction and inexpensive to manufacture it may be used as an advertising device and given gratis with the purchase of tooth paste; the upturned edge 4 of the shelf 3 and the lower edge of the back plate 1 permitting of advertising matter being easily 25 associated with the holder.

With the compartment plate 9 made of a thin gauge of material it will be more or less resilient and may be sprung under the 30 flanges 2 of the back plate with its frictional engagement with said plate preventing displacement, especially when withdrawing brushes from the compartments or in- closures.

One embodiment of my invention has 35 been illustrated, but it is to be understood that the structural elements are susceptible to such variations and modifications as fall within the scope of the appended claims.

40 What I claim is:—

1. A tooth brush holder comprising a flanged back plate having a shelf, and a compartment plate on said back plate and providing individual brush compartments 45 which have the upper ends thereof closed by the shelf of said back plate, said compartment plate possessing a resiliency which per-

mits of its side edges being sprung under the flanges of said back plate.

2. A tooth brush holder comprising two 50 plates detachably connected together, one of said plates having end flanges, the other of said plates having a configuration which cooperates with the first mentioned plate in providing brush compartments, the configuration of said plate causing its side edges to bind under the flanges of the first mentioned plate, and means between said plates adapted to hold brushes in the compartments. 60

3. A tooth brush holder as in claim 2, wherein said means is in the form of members out struck from the first mentioned plate.

4. A tooth brush holder comprising a back plate having an overhanging shelf, a compartment plate mounted on said back plate under said shelf, and cooperating with said back plate in providing a compartment having an open lower end, said compartment 70 plate having a configuration imparting resiliency thereto which causes said compartment plate to be frictionally held by said back plate, means adapted for fastening said back plate to a support with said means concealed by said compartment plate, and means struck out from said back plate and extending into the compartment adapted to retain a brush therein. 75

5. A tooth brush holder comprising plates 80 having the ends thereof connected with one of said plates having a scalloped configuration affording compartments and resiliency for maintaining the ends of said plates together, and the other plate having a configuration which affords resilient members to bind against the backs of brushes to be retained in the compartments. 85

In testimony whereof I affix my signature in presence of two witnesses.

WALTER W. WELPLEY.
